UNITED STATES PATENT OFFICE.

JOSEPH GILBERT, OF FREASES P. O., OHIO.

BUILDING CHIMNEYS.

Specification of Letters Patent No. 3,826, dated November 13, 1844.

To all whom it may concern:

Be it known that I, JOSEPH GILBERT, of 5
Freases P. O., in the county of Stark and
State of Ohio, have invented a new and
useful Improvement in the Construction of
Chimneys for Preventing Them from
10 Smoking, which is described as follows, refer-
ence being had to the annexed drawings
of the same, making part of this specifica-
tion.

Figure 1 is a perspective view of a section
of the chimney, showing a fire place
and flue and the channels left in the brick
work for the introduction of cold air to the
15 fire place, for increasing the draft of the
flue. Fig. 2 is a vertical section at the line
1, 1, of Fig. 3—showing the fire place, flue,
one of the channels, and the mantel. Fig. 3
20 is a horizontal section at the line X X of
Fig. 2, showing the fire place, channels,
valves or dampers and mantle.

I construct the chimney A in the usual
manner except in the particulars hereafter
described, constituting the improvements.
25 The back B of the fire place, I carry up in
the usual manner, near the level of the arch
of the fire place. I then carry it up vertical
at B², nearly to the level of the mantle, I
then cause it to retreat toward the back of
30 the stack, as at B³. Fig. 2 gradually enlarg-
ing the flue K. The arch and breast D, I
form in the usual manner. Immediately
35 above the fire place, I form a channel H,
around the fire place in the jambs and
breast, for the introduction of cold air to
the fire place, communicating with horizon-
tal channels E, passing transversely
40 through the chimney stack to the outside
thereof, for the introduction of cold air
from the outside of the building, opened or
closed by dampers I to regulate the admis-
sion of the air—the aforesaid channels in
the breast of the chimney, also communi-

cating with vertical channels L, formed in
the chimney stack, and communicating by 45
branch channels with the spaces between the
several floors, and the ceilings, for the in-
troduction of the cold air in said spaces, to
the fire place.

The pilasters and fascia, of the mantle 50
are placed over the above described chan-
nels around the fire place, thus forming the
front thereof. The lower portion of the
fascia of the mantle, is brought to a feather
edge, so as to form a horizontal longitudi- 55
nal space M, behind the mantle, communi-
cating with the horizontal air channel H in
the breast of the chimney, through which
space behind the mantle the cold air passes
from the aforesaid channels to the fire- 60
place—rushing by the intrados of the arch,
of the fire place to the throat thereof into
the partial vacuum, therein treated by the
rarefaction of the atmosphere in the chim-
ney, by the combustion of the fuel; and 65
thus causing a strong upward draft in
the flue, which carries off effectually all the
smoke in the fire place through the flue.
The admission of the cold air is regulated
70 by the aforesaid dampers I, and conse-
quently the draft of the chimney is in-
creased or diminished.

I do not claim admitting the external air,
for the purpose of preventing chimneys
from smoking, as that has been before done; 75
but

What I do claim, is—

The mode herein described of introducing
the air—that is to say, between the mantle
and the arch, in the manner and for the pur- 80
pose described.

JOSEPH GILBERT.
